(57) **CLAIM**

The ornamental design for a storage device for interconnection to the front of an automobile seat, as shown and described.

DESCRIPTION

FIG. 1 is a rear elevation view of the storage device for interconnection to the front of an automobile seat, showing my new design;

FIG. 2 is a front elevation view of the invention illustrated in FIG. 1;

FIG. 3 is a right elevation end view of the invention illustrated in FIG. 1;

FIG. 4 is a left elevation end view of the invention illustrated in FIG. 1;

FIG. 5 is a bottom plan view of the invention illustrated in FIG. 1;

FIG. 6 is a top plan view of the invention illustrated in FIG. 1; and,

FIG. 7 is a right front perspective view of the invention illustrated in FIG. 1.

The dashed lines on the storage device in FIGS. 1-4 and 7 are understood to represent stitching.
